No. 891,985.

PATENTED JUNE 30, 1908.

G. M. GALT.
PULP OR PAPER MACHINE.
APPLICATION FILED MAY 16, 1906.

UNITED STATES PATENT OFFICE.

GEORGE M. GALT, OF MALDEN, MASSACHUSETTS.

PULP OR PAPER MACHINE.

No. 891,985.

Specification of Letters Patent.

Patented June 30, 1908.

Application filed May 16, 1906. Serial No. 317,191.

To all whom it may concern:

Be it known that I, GEORGE M. GALT, residing in Malden, county of Middlesex, and State of Massachusetts, subject of the King of Great Britain, have invented certain new and useful Improvements in Pulp or Paper Machines, of which the following is a specification.

The invention aims to provide an improved machine for use in the manufacture of wet pulp or paper whereby the stock before leaving the felt is subjected to pressure, the first a gentle pressure which squeezes out a large part of the water and enables the stock to better stand the second which is a heavy pressure. The hydraulic pressure to which the stock is usually submitted makes holes in the felt by reason of the lumpiness of the stock or paste. These felts are very expensive and wear out very soon with the ordinary machines. By the first gentle pressure of the present machine, the paste is smoothed without seriously injuring the felts and passes to the point of the second pressure in a comparatively uniform and dry condition and the hydraulic pressure can act upon it more efficiently in this condition.

Preferably three rolls are employed to secure the desired pressures, the stock being pressed twice in passing around the middle roll. Separate pairs of rolls for the two different pressures may be used and any additional number of pressures may be applied. The important feature is to have a yielding pressure such as is obtained from springs, weights, or pneumatic devices or even a lighter hydraulic pressure, followed later by the usual heavy hydraulic pressure.

The accompanying drawings illustrate more or less diagrammatically a machine embodying the invention for use in the manufacture of box board.

Figure 1 is a side elevation, and Figs. 2, 3 and 4 are sectional views of details on an enlarged scale.

For the making of box board it is proposed to employ two machines arranged to face each other, the stock from the two machines being brought together to form a double thickness and being then carried away to the drying or calendering rolls. My improved pressing machine is especially adapted to this work because the stock leaves it in such a dry smooth condition that it is adapted to be handled and conveyed without breakage. The pressure machine, however, is

adapted to various other uses in connection with paper making. It is particularly useful as a wet pulp machine for forming the pulp into sheets.

In the embodiment of the invention illustrated the pressure machine is shown in connection with a drum A of any usual or suitable material, the stock being taken from the drum by a felt B running over a couch roll C and over a suitable suction device if desired. The pressure machine is shown as containing three rolls D, E and F arranged in the same vertical plane, the lower roll F being stationary and the other two vertically movable. The felt B runs over the first roll D and then between the two rolls D and E, around the back of the roll E and the front of the roll F and thence returns to the couch roll. It is given first a comparatively slight and preferably yielding pressure between the rolls D and E and then the usual heavy hydraulic rigid pressure between the rolls E and F. These pressures may be applied by a great variety of devices. The form shown is a very simple one consisting of springs G pressed downward on the bearing blocks H of the upper roll D, these bearing blocks being arranged to slide vertically upon the front portion of the frame J. Preferably a shaft K is provided having a collar bearing on the upper end of the spring G, the shaft being adapted to screw through a suitable portion of the frame J so as to increase or decrease the spring pressure on the bearing blocks H and so as to adjust the opposite ends of the roll relatively to each other.

The roll E is capable of a vertical movement. This is so slight as not to interfere with the proper operation of the yielding pressure roll D. The bearing blocks L for this roll are mounted on trunnions M on the frame J of the machine and are pivoted at their upper ends to links N of adjustable length connected to the short end of the lever O, the long end of which is connected to a piston P working in a hydraulic cylinder Q. The control of the hydraulic cylinder is omitted being well understood by those skilled in the art. In using this machine for making sheets of pulp, the pulp adheres to the intermediate roll E and follows around it until a sufficient thickness has been accumulated when the operator slits it longitudinally and draws off the sheet in the usual manner. When it is to be used for making paper the stock is separated from the felt after being

subjected to the pressure between the two lower rolls and issues in a continuous strip R. Where box board is to be made of two sheets then two machines may be arranged to face each other as shown and the strips R and R' issuing from the respective machines are brought together and pressed between rolls S and T (which are preferably arranged one above the other to economize space). Probably the strips R, R' will be sufficiently wet to adhere to each other. If not a paste applying device U may be arranged to apply paste to the inner face of either one of the strips. A considerable difficulty usually encountered in the making of this product is the presence of felt marks on the face of the finished product due to the roughness of the felt and the pressure of the individual strips between the felt on one face and the roll on the other face. By the arrangement shown the faces of the two strips R and R' which were in contact with the felt are brought together on the inside so that the exposed faces of the finished product will be those which traveled against the roll E and which were at no time in contact with the felt.

In order to carry away the water a doctor is preferably provided in the front angle between the rolls D and E. This doctor is preferably in the shape of a trough V arranged to receive the water which is squeezed out of the pulp at this point and to carry it away through a pipe W connected to the suction pump.

35 By the arrangement of the rolls one above the other as shown, the pressure between the two lower rolls is not only that due to the hydraulic pressure, but is increased by the weight of the roll E and also by the weight of the roll D and the pressure of the spring G, these last two being yielding pressures.

Though I have described with great par-

ticularity of detail the specific embodiments of my invention, yet it is not to be understood therefrom that the invention is limited to the particular embodiments disclosed. Various modifications thereof in detail and in the combination of the parts may be made by those skilled in the art without departure from the invention.

50 In some cases instead of using hydraulic pressure between the second and the lowest rolls E and F, I may use spring pressure the same as for the first two rolls. Preferably the machine is designed to use either or both, and the spring pressure is designed to be adjustable. For example the piston rod X may be provided with an extension Y projecting through the opposite end of the cylinder, and carrying a nut Z which forms an adjustable collar to receive the upward pressure of a spring a.

What I claim is:—

In a pulp or paper machine or the like, a pressure apparatus for pressing the water out 65 of the stock and comprising in combination three rolls arranged in the same plane the lowest roll E being rigidly mounted, pivoted bearing blocks L carrying the second roll, a hydraulic apparatus connected to said 70 bearing blocks L to press the lowest and the intermediate roll together with a hydraulic pressure, and sliding bearing blocks H for the uppermost roll and springs G engaging said bearing blocks H to press the upper two 75 rolls together with a yielding pressure.

In witness whereof, I have hereunto signed my name in the presence of two subscribing witnesses.

GEORGE M. GALT.
